7 Claims. (Cl. 133—8)

This invention relates to a coin counting apparatus, and more particularly to an apparatus for counting the number of coins, in which as coins to be counted are successively introduced, they are arranged edge to edge and substantially in a plane, and electrical connection there between is utilized for counting the number of the coins.

In automatic vending machines in which coins of different denominations may be introduced, it is necessary to separate the coins according to their denominations and separately count the number of coins of each denomination or to select among the coins those of a predetermined denomination and count the number thereof. In either case, it is required in view of the nature and function of the vending machine that the counting mechanism employed therein be quick and accurate in operation and simple in construction.

In one well known mechanism of the type, coins that have been introduced thereinto are held for a while in a slit provided with a number of microswitches so that each coin actuates each microswitch. The arrangement, however, not only results in the bulky size of the whole mechanism because it requires a number of microswitches and, consequently, a relatively large space for their installation, but also lacks in quickness in counting operation because it takes quite a time to clear the slit of the coins after the counting has been finished.

Accordingly, the principal object of the invention is to provide a new and improved mechanism which is capable of counting the number of coins held in a slit and which is speedy in operation and very simple in construction. The apparatus of the invention depends for its operation upon electrical conductivity of coins to be counted, the arrangement being simply such that the coins are piled up edge upon edge in a plane, preferably vertical, within a slit provided for the purpose. Switches such as microswitches can be dispensed with and, consequently, no space need be reserved for installing such switches, resulting in a great reduction in the size of the whole structure.

Another object of the invention is to provide a new and improved coin clearing mechanism of very simple construction which is capable of speedily and easily clearing of the space those coins held therein for counting when the counting operation has been finished. The apparatus of the invention is provided with a space or slit, defined at both sides by two spaced wall members, preferably vertical, and adapted to receive coins to be counted and hold them therein for a little while for counting. While thus held, the coins are piled up periphery upon periphery in a zigzag way and in such a manner as to be substantially included in a plane, and in this position the coins are held or supported by electrically conductive engaging members or rods projecting across the space or slit. Therefore, by withdrawing the engaging rods from their coin-holding position, the coins held thereby may be released therefrom to freely fall by gravity, and no energy, aside from that for such withdrawal of the engaging rods, need be externally given to make the coins fall.

Other objects, features and advantages of the invention will become apparent from the following detailed

description of some embodiments thereof with reference to the accompanying drawings wherein like reference numerals denote like parts and wherein:

FIG. 1 is a front view of the apparatus of the invention, with a portion of the front cover plate broken away to show the inside thereof;

FIG. 2 is a sectional side view taken along the line A—A of FIG. 1;

FIG. 3 is a block diagram of a counting circuit to be employed in the invention;

FIG. 4 is a wiring diagram of another counting circuit to be employed in the invention; and

FIG. 5 is a sectional side view similar to FIG. 2 but showing a part of another embodiment of the invention.

15 The apparatus of the invention comprises a space or slit adapted to receive coins to be counted, a plurality of electrically conductive engaging members projecting across the slit so as to engage and hold the coins, and means for counting the number of electrical signals produced as electrical connection between each pair of the engaging members is established.

20 Referring now in detail first to FIGS. 1 and 2, there is shown a space or slit 1 defined at both sides by a main wall plate 2 and a front cover plate 3 separated therefrom by a distance somewhat greater than the thickness of coins to be inserted. The plates 2 and 3 and, consequently, the slit 1 are shown standing vertical. This is most preferable, but it may be inclined either side so long as the inclination is such as to permit coins 25 held therein to fall by gravity when they are released, as will be described later. The two plates 2 and 3 are incorporated at their upper ends and pivoted on shafts 7. Coins to be counted of one and the same denomination are introduced into the slit 1 through its upper opening.

30 In automatic vending machines, the arrangement may be such that among those mixed coins which have been introduced thereinto only genuine ones are selected and then sent into a separator, where they are separated according to their denominations, after which coins of each 35 denomination or those of a predetermined denomination are counted. The slit 1 of the invention may be associated with the exit of such a coil separator.

35 The main wall plate 2 is provided adjacent its lower end with a pair of holes 4 and 5a and above these holes a plurality of holes as at 5b, 5c, 5d and 5e. The number of the latter holes may vary, depending on how many coins are to be held in the slit. The holes 4 and 5a are preferably horizontally spaced apart, while the latter four holes 5b, 5c, 5d and 5e are arranged in a zigzag way. By 40 "in a zigzag way" I mean this: On the surface of the main plate 2, from the central point of the hole 5a upward, draw a zigzag line having a plurality, say, three turning points and terminating in a fourth point, the five points being equidistantly spaced apart. Then form the four holes 5b, 5c, 5d and 5e at the latter four points, respectively, and they will be arranged in a zigzag way.

45 In the front cover plate 3, corresponding respectively to holes 4, 5a, 5b, 5c, 5d and 5e, there are formed six holes, of which holes 6a, 6c and 6e only are shown in FIG. 2. At the back of the main plate 2 and parallelly therewith, there is another vertical plate 8 pivoted at its upper end on shafts 7' and provided with a plurality of engaging members, here shown in the form of six pins or rods 9, 10a, 10b, 10c, 10d and 10e corresponding respectively to the holes formed in the main plate 2 and the front cover plate 3. The rods are made of electrically conductive material, each being intended to function as an electrical terminal as will be described later, and projecting laterally across the space or slit 1 through its corresponding hole in the plate 2 into its corresponding hole in the cover plate 3. Each of the rods is electrically insulated from the others by either making the rear plate

8 of insulating material or insulating the plate 8 from each of the rods. It is also required that when the rods are inserted through their respective holes in the plates 2 and 3, they are not electrically connected to the plates. To meet the requirement, the plates 2 and 3 may be made of insulating material, or the inner lateral surfaces of the holes formed therein may be coated with any suitable insulating material, or their diameter may be made large enough to avoid contact of the rods with the inner lateral surfaces of the holes when the former are inserted into the latter.

The distance between the rods 9 and 10a is somewhat smaller than the diameter of coins to be handled, and the distance between each neighboring two (on the zigzag line) of the rods 10a to 10e is somewhat smaller than twice the diameter of the coins. When several coins are dropped one after another into the slit 1, the first coin C₁ is arrested by the rods 9 and 10a so as to be held there; the next coin C₂ engages the periphery of the previous coin C₁ and also the rod 10b to be held above the coin C₁ somewhat to the right, as viewed in FIG. 1; and in a similar manner, the third coin C₃ is held above the coin C₂ somewhat to the left, the fourth coin C₄ above the coin C₃ somewhat to the right again, and the fifth coin C₅ above the coin C₄ to the left. Even if a sixth coin happens to fall in to hit on the periphery of the previous coin C₅, there is no more rod to support it so that it will be diverted through an opening 11 provided in the side wall 2' of the plate 2. In this manner, five coins, and not more than that, are piled up edge upon edge, arranged in a zigzag way and substantially included in a vertical plane. The number of coins to be held in the slit 1 may of course be varied as occasions demand.

It may happen that a coin having fallen into the slit 1 hits on the previously held coin to rebound therefrom to fly out either side through the space between the rods. To avoid such a trouble, a plurality, say, four projections 12a, 12b, 12c and 12d are provided across the slit 1 intermediate of each vertically adjacent two of the rods 9, 10a to 10e.

The cover plate 3 is provided on its outer surface with a bracket 14, to which is pivoted at 13 an armature 15 of an electromagnet whose coil 16 is connected through a normally open switch 18 to a suitable source of electricity 19. When the switch 18 is closed, the coil 16 is energized to attract the armature 15 in the direction of the arrow X, thereby causing the plates 2 and 3 to slightly pivot about the shafts 7. Similarly, the plate 8 is provided on its outer surface with a bracket 21, to which is pivotally connected at 20 an armature 22 of an electromagnet whose coil 23 is connected through a normally open switch 24 to a suitable source 25. When the switch 24 is closed, the coil 23 is excited to attract the armature 22 in the direction of the arrow Y, whereupon the plate 8 slightly pivots about the shaft 7' in the opposite direction to that in which the plates 2 and 3 are moved. Upon pivotal movement of the plates 2, 3 or the plate 8, the rods 9 and 10a to 10e are drawn out from their respective holes in the plates 2 and 3 and, consequently, from their respective coin-holding positions across the slit 1.

Directly under the lower and opening of the slit 1, there is provided a passage 26 for coins to drop into after the counting operation has been finished. Alongside the passage 26 there is provided another passage 27 the upper opening of which is positioned directly under the lower end opening of the slit 1 when the plates 2 and 3 have been moved together in the above mentioned manner.

Turning now to FIG. 3, wherein a counting device is shown in block diagram by way of example, the rods 10a to 10e, each made of electrically conductive material and intended to work as an electrical terminal, are connected to the inputs of well known amplifiers 31a, 31b, 31c, 31d and 31e through leads 32a, 32b, 32c, 32d and 32e, respectively. The rod 9 is grounded, and thence further connected to the amplifiers. The output sides of

the amplifiers are all connected to the input of a known counting device 34 through leads 33a, 33b, 33c, 33d and 33e, respectively. The arrangement of the device 34 may be such that it counts the number of output signals produced by the amplifiers, and when a predetermined number has been counted, it produces a signal at its output 35.

According to the invention, the counting operation is performed as follows. When the coin C₁ first to have fallen into the slit 1 has been arrested by the rods 9 and 10a, electrical connection between the two rods is established through the coin itself to complete the circuit to the amplifier 31a, whereupon the amplifier produces a signal at its output 33a, which will be transmitted to the counter 34. When the second coin C₂ has been held between the rod 10b and the periphery of the first coin C₁, the rods 9 and 10b are short-circuited through the two coins C₁ and C₂ so that the amplifier 31b produces a signal, which will be applied to the counter 34. In a similar manner, the coins C₃, C₄ and C₅ successively introduced into the slit are held by their respective rods 10c, 10d and 10e and the edge of the preceding coin, so that each of the coins successively connects that one of the rods 10c, 10d and 10e it has just engaged with to the rod 9 through itself and the coins previously held in their respective positions, whereupon each of the amplifiers 31c, 31d and 31e produces a signal, which will be applied to the counter 34. The illustrated embodiment is so arranged that five coins are to be held in the slit 1. If more coins are introduced into it, they are all rejected through the side opening 11.

Suppose that the counter 34 be so arranged that when five signals are applied to its input, it produces an output signal. Then, when the last coin C₅ contacts the rod 10e, thereby connecting this rod to the rod 9 through all the five coins that are held there, that is, when the amplifier 31e gives an output signal to the counter 34, the latter produces a signal at its output 35, which signal may be detected by any suitable known means to recognize that a predetermined number of coins have now been stored in the slit 1. In automatic vending machines, such a signal may be utilized to actuate means for delivering a piece of goods on sale to the hand of the buyer.

When the counting operation has been finished, the switch 24 is closed either manually or automatically by any suitable means upon production of an output signal by the counter 34. When the switch 24 is closed, the coil 23 is energized to attract the armature 22 in the direction of the arrow Y. This causes the plate 8 to pivot about shaft 7' until all the rods inserted into their respective holes in the plates 2 and 3 are withdrawn therefrom and from their coin-holding position across the space 1, whereupon the five coins losing their supports gravitate perpendicularly into the passage 26.

In automatic vending machines, when the number of coins that have been introduced thereinto happens to be less than the required number, or when the buyer changes his mind in the course of inserting coins, it is necessary to return the coins already introduced to the owner. When such necessity arises, the switch 18 is closed to energize the coil 16, which attracts the armature 15 in the direction of the arrow X, so that the plates 2 and 3 together pivot about shafts 7 until the lower end opening of the slit 1 comes to be positioned right above the upper opening of the passage 27. It will be readily seen that the pivotal movement of the plates 2 and 3 causes relative withdrawal of the rods supporting the coins from their respective holes formed in the plates 2 and 3, with the result that the coins gravitate perpendicularly into the passage 27, which may be so arranged that the coins will be returned to the hand of the buyer.

As described above, the circuit arrangement of FIG. 3 is such that as electrical connection between the rod 9 and each of the other terminal rods 10a to 10e is established, a signal is applied to each of the amplifiers 31a to 31e. The same may be effected by the arrangement of FIG. 4, wherein only so much is shown as is related

to the rods 9 and 10b. Between the two rods there is connected a series combination of a source 41 and a neon tube 42. A photoconductive element 43 is connected in the input circuit 32b of the amplifier 31b and is so disposed as to be able to receive light from the tube 42. When the 2nd coin C₂ connects the rods 9 and 10b through itself and the previous coin C₁, the tube 42 produces light. When the light is received by the element 43, the latter changes in resistance and, consequently, current through the input circuit 32b of the amplifier 31b changes to cause a signal to be produced at the output 33b and applied to the counter 34. As will be readily understood, the same arrangement applies with respect to the rod 9 and each of the rods 10a, 10c to 10e.

In the embodiment of FIGS. 1 and 2, in order to clear the coins of the slit 1 after completion of the counting operation, the rear plate 8 is slightly moved about the shafts 7'. However, it is not necessary to withdraw all the rods out of their respective holes in the plates 2 and 3, but either one of the lowest rods 9 and 10a only needs to be withdrawn from their respective coin-holding position across the slit 1 in order for the coin C₁ to gravitate out of the slit 1, necessarily followed by all the other coins.

FIG. 5 shows by way of example a device for drawing either one of the lowest two rods 9 and 10a out of their respective holes in the plates 2 and 3. In this case, the rod 9 or 10a is made of magnetic substance to serve as a plunger for a coil 51 connected between terminals 53 of a source of electricity through a normally open switch 52. When the switch is closed, the coil is excited to attract the rod 9 in the direction of the arrow Z to be drawn out of the slit 1.

It is now believed to have become clear that the present invention has various advantages such as follows: Accuracy and quickness in counting operation is ensured through utilization of the conductivity of coins to be counted. It is not necessary to provide any switches to be actuated by coins and, consequently, to have a considerably large space reserved for them, as in the prior art. This greatly reduces the size of the whole structure of the apparatus. In order to discharge the coins from the slit after counting operation, no energy need be externally given to the coins and no complicated means for the purpose is required, except that for the withdrawal of the rods from coin-holding position. It is also possible to return the coins already introduced to the owner during the course of buying action.

It should be recognized that the embodiments disclosed herein are merely representative, and that modifications and changes may be made without departing from the true scope and spirit of the invention.

I claim:

1. Apparatus for counting the number of coins comprising: a pair of wall members spaced apart to define a space therebetween into which coins to be counted are to be introduced; a plurality of engaging members of electrically conductive material, each being insulated from the others and intended to function as an electrical terminal, said engaging members projecting across the space between the wall members and so arranged in a substantially zigzag pattern along the length of the space that the coin first to have fallen into the space is held by the lowest two of the engaging members and the successively following coins are held by successive ones of the other engaging members and the edge of the previously held coin in a predetermined and fixed zigzag pattern arrangement; and counting circuit means for counting the number of output signals produced as electrical connection is established between a specific one of the engaging members and each of the rest thereof.

2. Apparatus for counting the number of coins comprising: a pair of wall members spaced apart to define a space therebetween into which coins to be counted are to be introduced; a plurality of engaging members

of electrically conductive material, each being insulated from the others and intended to function as an electrical terminal, said engaging members projecting across the space between the wall members and so arranged in a substantially zigzag way along the length of the space that the coin first to have fallen into the space is held by the lowest two of the engaging members and the successively following coins are held by each of the other engaging members and the edge of the previously held coin; and counting circuit means for counting the number of output signals produced as electrical connection is established between a specific one of the engaging members and each of the rest thereof, said counting circuit means including a neon tube and a photoconductive element, said tube being so arranged as to produce light as electrical connection is established between said specific one of the engaging members and each of the rest thereof, while said photoconductive element is so arranged as to receive the light from the tube and produce a signal to be applied to a counter.

3. Coin counting apparatus comprising in combination: first and second wall members; means spacing said members apart in parallel relationship to define a coin receiving space therebetween having an entrance opening for the receipt of coins and a discharge opening for the discharge of coins; first and second electrically conductive coin engaging members extending into said space near said discharge opening for engagement by the first coin of a group to be counted, the separation between said engaging members being less than the diameter of the coins to be counted to thereby trap the first such coin inserted into said space; a third electrically conductive coin engaging member extending into said space between said first engaging member and said entrance opening and located a distance from said second engaging member which is less than twice the diameter of coins to be counted and located closer to said first engaging member than to said second engaging member; a fourth electrically conductive engaging member extending into said space at a point between said second engaging member and said entrance opening and located a distance from said third member which is less than twice the diameter of coins to be counted, said fourth member being closer to said entrance opening than said third member and closer to said second member than to said first member; means maintaining each of said first, second, third, and fourth members insulated from each other in the absence of coins; circuit means coupled with one of said first and second members and adapted to energize the other three of said engaging members sequentially as successive coins engage a preceding coin and one of said members; and counting means coupled with said other three members.

4. Coin counting apparatus comprising in combination: a pair of wall members spaced apart to define a substantially vertical coin receiving slot having a receiving opening and a discharge opening; first and second electrically conductive coin holding members disposed in said slot and separated by a distance less than the diameter of coins to be counted; means defining a zigzag coin holding space between said first and second coin holding members and said entrance opening for holding coins substantially co-planar in a predetermined zigzag pattern with a first coin being held between said first and second members and succeeding coins engaged with the edge of a preceding coin; said means including a plurality of conductive coin engaging members disposed in said slot between said receiving opening and said first and second members and alternating in relation to said first and second members and to said second holding member to form a zigzag pattern thereof; circuit means energizing one of said holding members; and counting means coupled with the other of said holding members and with each of said engaging members and responsive to the successive energization thereof.

5. Apparatus as defined in claim 4 wherein adjacent ones of said engaging members are separated by a distance which is less than twice the diameter of coins to be counted.

6. Apparatus as defined in claim 4 wherein said zigzag pattern has three turning points with one of said engaging members located at each turning point and a fourth engaging member at the termination of the zigzag pattern. 5

7. Apparatus as defined in claim 4 wherein alternate ones of said engaging members are separated by a distance greater than the diameter of coins to be counted, and including coin deflecting means positioned between alternate ones of said engaging members to prevent the passage of coins therebetween and to cause successive 10

coins to always engage said engaging members in a fixed sequence.
